UNITED STATES PATENT OFFICE.

ROBERT K. SLAUGHTER, OF BROOKLYN, NEW YORK, ASSIGNOR TO LOUIS GREENBAUN & SON, OF NEW YORK CITY.

DESIGN FOR TASSEL-DROPS.

Specification forming part of Design No. 7,714, dated August 25, 1874; application filed August 10, 1874.
[Term of Patent 3½ years.]

CASE D.

To all whom it may concern:

Be it known that I, ROBERT K. SLAUGHTER, of Brooklyn, Kings county, New York, have invented a Design for a Tassel-Drop, of which the following is a specification:

The nature of my design is fully represented in the accompanying photographic illustration, to which reference is made.

The main part *a* of the design is in the shape of an inverted frustated cone, whose lower rounded-off part is fluted, while the larger upper part is covered with a netting, *a'*. Above the cone part *a* are arranged five parts, of smaller size, a frustated cone, *b*, with circumferential band or strip, being placed next to it, and a similarly-shaped inverted cone, *e*, above the intermediate fluted disk *d*, of large diameter. A conical striped or trimmed piece, *f*, is placed above the inverted cone *e*, and capped by a spherical crown or top part, *g*. A spher-

ical part, *h*, of the same size forms the lowermost part or point of the drop below the main cone *a*. The parts are strung up in the usual manner on a central connecting-cord, and spun over with suitable material in appropriate colors for producing the configuration and ornamentation shown.

I claim as my invention—

The design for a tassel-drop composed of the inverted conical and rounded-off main part *a* with the conical part *b*, the fluted disk *d*, the inverted conical part *e*, the striped conical part *f*, and the spherical crown part *g* above the same, and a spherical point or bottom part, *h*, below the same, as shown and described.

ROBERT K. SLAUGHTER.
